UNITED STATES PATENT OFFICE.

STANLEY BARDAXOGLOU, OF NEW YORK, N. Y.

MILK-BOTTLE PROTECTOR.

Application filed April 9, 1927. Serial No. 182,491.

This invention relates to improvements in theft preventing devices and more particularly to a device for protecting milk bottles from being stolen or misappropriated by unauthorized persons.

It is the principal object of my invention to provide a simple and inexpensive device adapted to be readily combined with any house door or other part of a house and 10 adapted to receive a milk bottle delivered by the milkman, who then turns the protecting cover and bottle therein so that the bottle can be removed only from the interior of the house, while the protector is automatically 15 locked in this position against rotation.

Another object of the invention is the provision of a milk protector which may readily allow its attachment to any delivery box and which is equipped with a spring supported 20 platform adapted to receive the bottle, the tension of the springs being so selected that the weight of the bottle and milk therein is sufficient to overcome their tension to allow the locking pin to enter a suitable keeper hole 25 in the door or box frame to lock the protector in its bottle protecting position.

A further object of my invention is the provision of a milk bottle protecting device of this character equipped with a half-cylindrical protecting cover surrounding the bottle on its supporting platform, and rotatably arranged in the door or other frame which for this purpose is provided with an opening just large enough to allow a freely turning 35 of the protecting mantle or cover.

These and other objects and advantages of my invention will become more fully known as the description thereof proceeds, and will then be more specifically defined in the appended claims.

In the accompanying drawing, forming a material part of this disclosure:

Fig. 1 is a rear view of the milk bottle protecting device constructed according to 45 my invention, locked.

Fig. 2 is a front view thereof.

Fig. 3 is a cross-section on line 3—3 of Figure 1.

Fig. 4 is a fragmentary detail view of the 50 lower part of the milk bottle protector showing the bottle supporting platform after the removal of the bottle.

As illustrated, a door or other frame 10 has provided therein a longitudinally extending vertical slot 11 limited at its inner face 55

by a surrounding frame 12 or the like. In this slot is rotatably arranged a half-cylindrical body 13 open towards one side and turning about the upper pin 14 and the lower pin 15 projecting from the door frame into the top and bottom wall of the body respectively, the lower end of the body being suitably guided in a guide 16 or the like.

A bottle supporting platform 17 is normally held in its elevated position by means 65 of a plurality of supporting springs 18 attached at their upper ends to the lower face of the platform and adapted to engage the guide 16 with their lower ends. A pin 19 depends for a certain length from the lower 70 face of the platform at a certain predetermined point thereof, and is adapted to engage upon the compression of the springs by the weight of a milk bottle 20 and its contents an opening in the guide and in the bottom 75 part of the door frame, as indicated at 21.

The central pin 15 attached to the lower face of the platform serves also as lower pivot point for the body, as it is adapted to engage a suitable bore in the door frame as 80 indicated at 22. The half-cylinder body can be provided with suitable inscriptions on its front, for instance such as shown "Milk protector" and a star or the like.

The operation of my device will be entirely 85 clear from the above description by comparison with the drawing.

The half cylindrical body is turned with its open side face towards the exterior of the building or box, and the delivering milkman places a full bottle of milk upon platform 17 compressing the springs and engaging the lower end of pin 19 with the frame until it arrives during the turning motion of the body over the bores in guide 16 95 and frame. The tension of the springs is so selected that the weight of the bottle and its contents will compress the springs to such a degree that the locking pin 19 can readily engage the bores 21 to lock the body which has been turned by the delivering person with its closed side towards the outside preventing the bottle from being reached from the outside, while it can conveniently be removed from the inside of house or box.

It will be understood that I have shown and described the preferred form of my device as an example only of the many ways in which the same may be constructed, and that I can make such changes as come within 105 110

the scope of the appended claims in its construction without departure from the spirit of my invention.

Having thus described my invention, what I claim as new and desire to secure by Letters Patent is:

1. Milk bottle protector comprising a half-cylindrical hollow body open towards one side, means for allowing a rotation of said body within an opening in a door frame, a platform within said body adapted to receive the milk bottle, a plurality of springs supporting said platform, a depending pin on said platform adapted to enter a bore in the door frame upon the depression of the platform under the weight of a full bottle placed thereon to constitute a locking means, said locking means being located at predetermined points, and said yielding platform supporting means of a tension to ensure the proper operation of said locking means for holding the closed bottle protecting side of said body towards the outside of a building to prevent a theft of the bottle and tampering with the bottle contents after delivery of the bottle.
2. Milk bottle protector comprising a half-

cylindrical hollow body open towards one side, pins entering said body from opposite ends for allowing a rotation of said body within an opening in a door frame, a guide for the lower end of said body, a platform within said body adapted to receive the milk bottle, a plurality of means for yieldingly supporting said platform, a depending member on the bottom of said platform adapted to enter a bore in the door frame upon the depression of the platform under the weight of a full bottle placed thereon to constitute a locking means, said locking means being located at predetermined points, and said yielding platform supporting means of a tension to ensure the proper operation of said locking means for holding the closed bottle protecting side of said body towards the outside of a building to prevent a theft of the bottle and tampering with the bottle contents after delivery of the bottle.

Signed at New York, in the county of New York and State of New York, this 7th day of April, A. D. 1927.

STANLEY BARDAXOGLOU.
